UNITED STATES PATENT OFFICE.

JOHANN KEINEDER, OF ASTORIA, NEW YORK.

LOOM.

1,318,498.

Specification of Letters Patent.

Patented Oct. 14, 1919.

Application filed June 5, 1917. Serial No. 173,046.

To all whom it may concern:

Be it known that I, JOHANN KEINEDER, a subject of the Emperor of Austria, resident of Astoria, county of Queens, and State of New York, have invented certain new and useful Improvements in Looms, of which the following is a specification.

This invention relates to improvements in apparatus for producing relatively coarse, 10 textile fabrics, in the nature of a hand operated loom.

The principal object of the invention is to provide an apparatus which facilitates the weaving of the cords used, thereby 15 structuring fabrics such as mats, rugs, and the like, relatively small in size, thick and strong in their nature.

A further object is to provide means whereby the warp threads may be turned 20 axially permitting easy entrance of the filling threads between them.

A still further object of the invention is to provide means whereby the threads of the warp are alternately separated for the 25 passage of the weft or filling threads, the operation being controlled by a single movement only, and finally, to provide an apparatus comprised of few and simple parts, of cheap construction.

30 These and other like objects are attained by the novel construction and combination of parts hereafter described and shown in the accompanying drawings, forming a material part of this specification, and in 35 which:—

Figure 1 is a partial front elevational view showing an embodiment of the invention.

Fig. 2 is a vertical sectional view taken on 40 line 2—2 of Fig. 1.

Fig. 3 is a top plan view of the apparatus, parts being broken away to disclose the construction.

Fig. 4 is a top plan view showing another 45 modification.

Fig. 5 is a side view of the same.

The apparatus consists of an end or base plate 15, to the ends of which are attached standards 16 extending to a plate 17, forming the base of the mechanism casing, which 50 is comprised of side walls 18 and a cover plate 19 at the top.

A bar 20 is adapted to engage the standard 16, held therein by pins 24, the same 55 being engageable with perforations 25 formed through the standard 16 so that the

bar may be adjusted at any desired height, the bar carrying a plurality of oppositely disposed hooks 28, similar hooks 30 extending downward through the plate 17, their 60 upper ends or shanks 31 passing rotatably through a fixed plate element 32 secured in the casing between the side walls 18 in such manner as to sustain the shanks 31 by raising the collars 33 secured to them, pins 34 65 passing through the shanks beyond the collars, one of each row of shanks projects upwardly through the plate 19 and has attached to it a handle 35 by means of which the shank is turned, and secured to all of 70 the several hooked shanks are pairs of ears 38 adapted to receive between them bars 40, the same being held in position by the pins 41 passing through the ears and bars in such manner that as the bars are given reciprocating motion, the hooks are caused to oscillate, thereby turning the bight formed in the upper looped ends 44 of the longitudinally disposed cords or warp 45, so as to permit the transverse cord or filling 46 to 80 pass between alternate strands in the manner indicated in Fig. 1.

In Figs. 4 and 5 an alternative method of oscillating the hook stems is presented, a series of pinions 50 being secured to the extending stems of the hooked shanks 31, similar pinions 52 being disposed upon the adjacent row of shanks and all of which are rotatable through the train of pinions actuated by the miter gears 53, one of which is 85 secured to the shaft 54, which extends outwardly at one side of the frame, and is furnished with an operating handle 55.

From the foregoing, it will be seen that a simple but highly efficient apparatus has 95 been disclosed, materially assisting the weaver of coarse fabrics of the kind indicated, from material like coir, hemp, twines, straw, coconut fibers, reed, rushes, etc., etc.

Having thus described my invention, what 100 I claim as new, and desire to secure by Letters Patent, is:—

In a device of the character described, the combination of a base plate with a mechanism casing, of standards supporting said 105 casing upon said base-plate, a bar engaged between said standards, oppositely disposed lower hooks on said bar, similar, upper hooks extending through the bottom of said casing, a fixed element in said casing 110 through which the shanks of said last named hooks extend, collars on said shanks, one of

each row of said shanks extending through the top plate of said casing, a handle attached to the upper end of said shank, pairs of ears on said shanks in said casing, bars 5 between the ears and pins passing through said ears and bars, said pins allowing the bars to be given a reciprocating motion for

oscillating the hooks to turn the bight formed in the warps secured to the upper and lower hooks for permitting the passage 10 of the filling cord between alternate strands.

In testimony whereof I have affixed my signature.

JOHANN KEINEDER.

Copies of this patent may be obtained for five cents each, by addressing the "Commissioner of Patents, Washington, D. C."
